(57)

CLAIM

The ornamental design for a bolt, as shown and described.

DESCRIPTION

FIG. 1 is a perspective view of a bolt showing my new design;
 FIG. 2 is a front view thereof;

FIG. 3 is a back view thereof;

FIG. 4 is a top view thereof;

FIG. 5 is a bottom view thereof;

(Continued)

FIG. 6 is a right-side view thereof; and,
FIG. 7 is a left-side view thereof.

1 Claim, 4 Drawing Sheets
